UNITED STATES PATENT OFFICE.

FREDERICK C. BONNET, OF HAMBURG, NEW YORK, AND RAYMOND FRANKLIN, OF DURANT, OKLAHOMA.

OIL-WELL FISHING TOOL.

Application filed January 3, 1922. Serial No. 526,676.

To all whom it may concern:

Be it known that we, FREDERICK C. BONNET and RAYMOND FRANKLIN, citizens of the United States, residing, respectively, at Hamburg, in the county of Erie and State of New York, and Durant, county of Bryan, and State of Oklahoma, have invented a new and useful Improvement in Oil-Well Fishing Tools, of which the following is a specification.

This invention relates to improvements in tools of the kind commonly called fishing tools and which are used for the purpose of removing pieces or parts of drilling equipment or the like from an oil well.

Fishing tools as heretofore made usually include a slip socket of some sort which is adapted to be slipped over the end of the broken tool or other part which is to be removed from an oil well, and these implements are very satisfactory in their operation when the part to be removed is substantially centrally located within the well. If, however, the part is located at an inclination to the axis of the well, in such a manner that the fishing tool cannot be slipped over the part to be removed, great difficulty is experienced in removing the part which is so positioned.

The objects of this invention are to provide a fishing tool of the usual kind with a magnetic attachment whereby an article or part to be removed from a well may be moved into a position to be engaged by the usual slip socket; also to improve the construction of oil well fishing tools of this kind in the other respects hereinafter specified.

In the accompanying drawings:

Fig. 1 is a sectional elevation of a fishing tool provided with a magnetic attachment embodying the invention, showing the same arranged in an oil well.

Fig. 2 is a central sectional elevation of the magnetic device.

Fig. 3 is a top plan view thereof, partly in section.

A represents a slip socket or gripping device which may be of any usual or suitable construction, that shown being of a type commonly used, including a pair of gripping members *a a*, provided on their inner faces with teeth adapted to engage the article to be removed from the well and having their outer faces formed to cooperate with

inclined faces *a' a'* of the slip socket. The gripping members are slidably arranged in the body portion of the slip socket and are moved upwardly by an article entering the socket and are drawn downwardly against the inclined faces and into gripping engagement with an article when the same is moved outwardly with reference to the slip socket. The upper end of the socket is provided with the usual threaded stem *a²* adapted to engage some portion of the well drilling device indicated in dotted lines at *a³* in Fig. 1. When a slip socket of this kind is lowered into a well to remove an article such, for example, as indicated by B in Fig. 1, the slip socket is lowered so that the article enters into the same. When the slip socket is raised, the teeth of the gripping members *a* hold the article B and make it possible to extract the same from the oil well. When, however, an article becomes lodged in a well in the manner shown, for example, in dotted lines at B', Fig. 1, a slip socket of this kind cannot be successfully used, since in lowering the same the article will not enter into the slip socket, but will tend to become lodged more securely in its inclined position by the weight of the slip socket bearing thereon.

In order to bring the upper end of the article to be removed from the well into substantially the center of the well, in which position it can be engaged by any of the fishing tools commonly used, we provide a magnet, preferably an electromagnet which is so constructed as to draw the upper end of the article substantially into the central axis of the well. In order to enable the magnet to act in this manner upon the article, the magnet is preferably made hollow, being in the construction shown, provided with a tubular core which is made large enough to permit the article to be removed from the well to enter into the hollow core. In the construction shown, an electromagnet is used having a hollow or tubular core C around which a winding or coil D is arranged, the core being made of magnetic material. The upper end of the core is preferably arranged in such a way that the magnet can be supported from the lower end of the slip socket and for this purpose a threaded bushing or sleeve E is provided, having a threaded engagement with the upper end of the core C and also adapted to engage the lower end of the slip socket A for se-

surely holding the electromagnet on the end of the slip socket. By means of the relative arrangement shown of the magnet and slip socket, an article, after passing through 5 the core of the magnet, enters into the slip socket into a position to be engaged thereby. The bushing or sleeve E is preferably, though not necessarily, made of non-magnetic material so as to avoid excessive magnetizing of the slip socket, which might in 10 some cases interfere with the proper operation thereof. Any other means for securing the magnet on the end of the slip socket may be provided. The outer face of the 15 winding or coil D may be covered with a protecting sleeve or shield F or the like.

In order to enable the device to operate in such a manner as to move the article in 20 the well toward the central axis of the well, the lower end of the magnet is provided with a ring or sleeve G of non-magnetic material. This ring may be of any suitable or desired form, that shown being provided with a beveled, inner face g and is secured to the 25 lower end of the core C in any suitable manner, for example by means of screw threads. When the magnetic device is in close proximity to the upper end of the article to be removed from the well, the magnetism acts 30 in such a manner as to tend to draw the upper end of the article in the well toward the central axis of the well. This is due to the fact that the ring G of non-magnetic material prevents the magnetism from being 35 concentrated at the lower edges of this ring, as would happen if the ring G were made of magnetic material, in which case the article in the well would tend to adhere to the lower extremity of the ring and would 40 not tend to straighten out or move into the central axis of the well. Since the ring G is made of non-magnetic material the greatest magnetic force is exerted at the lower end of the hollow core C, which is arranged 45 within the bell-shaped mouth of the ring G. Consequently the hollow core C tends to attract the article in the well and to act upon the same in such a manner as to move it toward the central axis of the well, and 50 when the article assumes this position, the magnet, together with the slip socket, is lowered so that the article passes through the hollow core C and upwardly into the slip socket, where it is engaged by the 55 toothed gripping members a in the usual manner. The article can then be readily removed from the well.

d d' represent a pair of conductors connected with the ends of the coil D of the 60 electromagnet and extending through the slip socket A, the conductors extending upwardly out of the well.

In the use of the magnet for recovering an article lost in an oil well, the magnet 65 attached to the gripping device or slip socket

is lowered into the well until it rests on the article to be recovered. Electric current is then passed through the magnet coil and energizes the core. The magnet is then raised slightly so as to permit the article to move toward the central axis of the well, due to magnetic action. The magnet and the gripping device connected therewith are then lowered so that the article passes upwardly through the hollow core and into engagement with the gripping members of the slip socket. The magnetism is then no longer needed so that the supply of current to the magnet coil may be interrupted. The magnet need not be in any way depended upon to raise the article out of the well, but serves for the purpose of placing articles into positions to be engaged by the gripping device. It will be noted that by providing the non-magnetic ring G with an inner beveled face, the magnetism need not move the article into an entirely central position, it being only necessary to move the article into a position in which the non-magnetic ring may slip over the upper edge 90 of the article, whereupon the beveled inner face of this ring will guide the article and slip socket into engagement with each other.

We claim as our invention:

1. In a device for removing articles from wells, the combination of a slip socket and a hollow magnet secured to the lower end of the slip socket and through which an article to be removed from a well may pass to the slip socket for engagement therewith.

2. In a device for removing articles from wells, the combination of a gripping device adapted to engage an article, and a hollow magnet arranged below said gripping device and adapted to move the article into a position to be engaged by said gripping device.

3. In a device for removing articles from wells, the combination of a gripping device adapted to engage an article, a hollow magnet arranged below said gripping device and adapted to move the article into a position to be engaged by said gripping device, and a ring of non-magnetic material secured to the lower end of said magnet and which causes the magnet to move the article into a central position in the well.

4. In a device for removing articles from wells, the combination of a gripping device adapted to engage an article, and an electromagnet arranged below said gripping device and having a hollow core which is substantially in alignment with said gripping device, whereby the magnetism in said core draws the article substantially into the central axis of the well, permitting the article to pass through said core into engagement with said gripping device.

5. In a device for removing articles from

- wells, the combination of a gripping device adapted to engage an article, an electromagnet arranged below said gripping device and having a hollow core which is substantially in alignment with said gripping device, and a ring of non-magnetic material secured to the lower end of said core and extending below the same, whereby the magnet, when in proximity to the article, will tend to move the article toward the axis of the well. 6. In a device for removing articles from wells, the combination of a gripping device adapted to engage an article, an electromagnet arranged below said gripping device and including a coil, a tubular core about which said coil is arranged, said core extending below said coil, and a ring of non-magnetic material arranged on the lower end of said core and extending below the same. 7. In a device for removing articles from wells, the combination of a gripping device adapted to engage an article, an electromagnet arranged below said gripping device and including a coil, a tubular core about which said coil is arranged, said core extending below said coil, and a ring of non-magnetic material arranged on the lower end of said core and extending below the same and having an inner beveled face, the upper edge of which terminates at said core. 8. In a device for removing articles from wells, the combination of a gripping device adapted to engage an article, and a coil of wire suitably mounted on the lower end of said gripping device and adapted to be energized by electric current to move an article toward the central axis of the well. 9. In a device for removing articles from wells, the combination of a gripping device adapted to engage an article, an electromagnet arranged below said gripping device and including a coil, a tubular core about which said coil is arranged, a non-magnetic member adapted to be secured to the lower end of said gripping device and to said core for supporting said core on said gripping device, and a non-magnetic ring secured to the lower end of said core and adapted to hold the article out of engagement with said core until the article has been moved into a substantially central position in the well.

FREDERICK C. BONNET.
RAYMOND FRANKLIN.
